Des. 241,058
Patented Aug. 17, 1976

241,058

FLOWER POT

Frederick A. Burke, Riverside, Conn., Joel A. Farrell, Carlisle, Mass., and Douglas A. Long, Wilton, Conn., assignors to The Gillette Company, Boston, Mass.

Filed Aug. 13, 1975, Ser. No. 604,105

Term of patent 14 years

Int. Cl. D11—02

U.S. Cl. D35—3 A

FIG. 1 is a perspective view of a flower pot showing our new design;

FIG. 2 is a side elevational view thereof, all four sides being substantially the same;

FIG. 3 is a top plan view thereof; and

FIG. 4 is a bottom plan view thereof.

We claim:

The ornamental design for a flower pot, substantially as shown.
